UNITED STATES PATENT OFFICE

110,467

DESIGN FOR A PENCIL

James J. Sanders, Nashville, Tenn.

Application May 19, 1938, Serial No. 77,283

Term of patent 14 years

To all whom it may concern:

Be it known that I, James J. Sanders, a citizen of the United States, residing at Nashville, in the county of Davidson and State of Tennessee, have invented a new, original, and ornamental Design for a Pencil, of which the following is a specification, reference being had to the accompanying drawing, forming part thereof.

Fig. 2 is an end or tip view of the pencil showing the multi-color leads, and

Fig. 3 is an enlarged fragmentary side view of the pencil showing more clearly the surface ornamentation seen on the body of the pencil in Fig. 1.

I claim:

The ornamental design for a pencil, as shown and described.

JAMES J. SANDERS.
